Los Angeles, Calif.; said Wallner assignor to
Wentworth

Application September 22, 1933, Serial No. 690,586

3 Claims. (Cl. 257—130)

The invention herein disclosed relates to radiators and is particularly directed to that general type of radiator adapted for use as a unit of the water cooling system of an internal combustion engine. More specifically the invention concerns what is generally referred to as the radiator core and which ordinarily includes a plurality of spaced water circulating tubes or conduits associated with suitable means for entraining cooling air between said tubes or conduits, it being an object of the invention to provide an improved radiator core construction including air entraining means between adjacent fluid circulating members with said air entraining means formed to provide series of transverse air passages extending from front to rear of said core and to provide air deflecting elements arranged to split the air entrained through said passage and deflect the split air currents into the adjacent air passages.

Another object is to arrange certain of said deflecting elements to deflect some of said split air currents towards said fluid circulating members and to arrange other of said deflecting elements to deflect other of said split air currents away from said fluid circulating members.

Another object is to angle said deflecting elements to deflect said split air currents obliquely to increase the cooling effect of said deflected split air currents by thus increasing their distance of travel before being discharged from the radiator core.

A further object is to angle some of said deflecting elements upwardly and rearwardly to direct some of said split air currents in an oblique direction upwardly and rearwardly across the adjacent transverse air passages and to angle others of said deflecting elements downwardly and rearwardly to direct others of said split air currents in an oblique direction downwardly and rearwardly across the adjacent transverse air passage.

Another object is to provide additional reversely facing similar deflecting elements whereby the air entraining means will function similarly on air entrained through the radiator in either transverse direction.

Various other objects and advantages will be more fully apparent from the following description of the accompanying drawing which forms a part of this disclosure and which illustrates a preferred form of embodiment of the invention.

Of the drawing:

Fig. 1 is a front elevation of a portion of a radiator core embodying the features of the in-

vention, part thereof being in section to disclose the configuration of the fluid circulating conduits.

Fig. 2 is a section taken on the line 2—2 of Fig. 1.

Fig. 3 is a section taken on the line 3—3 of Fig. 1.

Fig. 4 is a detail perspective view of a portion of the radiator core, partly broken away and with a portion of one of the air-deflecting plates separated therefrom and turned over to show its reverse side.

Fig. 5 is a front elevation showing a modification in which one of the improved air-deflecting plates is associated with two adjacent zig-zag fluid circulating conduits.

Fig. 6 is a front elevation of another modification in which the improved air-deflecting unit comprising a pair of said air-deflecting plates is associated with two adjacent parallel straight fluid circulating conduits.

Fig. 7 is a front elevation of a further modification in which a single air-deflecting plate is associated with two adjacent parallel straight fluid circulating conduits.

The core of a radiator of the general type to which the present invention relates, usually comprises a plurality of vertically disposed fluid circulating conduits spaced apart by means constructed to provide air passages through which cooling air is forced to effect a transfer of heat from the conduits to the air entrained through the core. In the preferred embodiment illustrated in Figs. 1 to 4, the several fluid circulating conduits or water tubes A are disposed vertically in transversely spaced relationship and are separated by intermediate air-deflecting units B. Each tube A is preferably formed of a pair of relatively thin plates 10 and 11 transversely corrugated and disposed to intermesh with each other, the intermeshing longitudinal edge portions being joined together at 12, 12 and their intermediate portions being spread apart to provide a zig-zag fluid passage 13. At opposite ends of each crest these plates 10 and 11 are provided with pairs of relatively short ridges 10^a and 11^a defining relatively short intermediate indentations or pockets which receive the respective crests of the adjacent corrugated air-deflecting plates as will later be more particularly described.

The several air-deflecting units B are of duplicate construction, each comprising a pair of relatively thin plates 20 and 21 transversely corrugated and disposed in crest coengaging relationship to provide a vertical series of inner air pas-

sages B² and two vertical series of outer air channels B³ between the outer wall of each plate and the adjacent wall of the next adjacent fluid conduit A. The several coengaging crests of these plates 20 and 21 are provided with pairs of relatively spaced tangs 20^a and 21^a stamped from the bodies of the respective plates and bent outwardly as shown in Fig. 4. When the several parts of the core are assembled, these pairs of tangs embrace the coengaged inner crests of the two air-deflecting plates and the outer crests of said plates engage the adjacent fluid conduits in the pockets formed by the respective ridges 10^a and 11^a thereof, these tangs and ridges thus providing means for maintaining the parts in proper alignment during assemblies. In the manufacture of the core it is preferable to first assemble the several parts and then secure the assembled parts together, by dipping the assembled core in molten solder or in any other suitable manner, to form a permanently joined unit.

The two plates 20 and 21 forming each air-deflecting unit B are of duplicate contour and construction but when brought together in crest co-engaging relationship they are first transversely reversed, that is, they are turned so as to bring one longitudinal edge of each plate adjacent the opposite longitudinal edge of the other plate. This will be understood from an examination of Fig. 4 wherein the tangs 20^a of the plate 20 are positioned towards the rear of the core while the tangs 21^a of the plate 21 are positioned towards the front of the core.

35. Describing each of the air-deflecting plates separately, a transverse wall 20^b on one side of each inner crest 20^c of the plate 20 is provided with apertures 20^d disposed at transversely spaced intervals, and is deformed adjacent the rear edge of each of said apertures to provide deflecting elements 20^e projecting into the adjacent inner air passage B² and facing the entrance end of said passage. The transverse wall 20^m on the other side of each inner crest 20^c is provided with similar apertures 20ⁿ disposed at transversely spaced intervals staggered with relation to the apertures 20^d of the opposite wall and said wall 20^m is deformed adjacent the rear edge of each of said apertures to provide other deflecting elements 20^e projecting into the adjacent outer air channel B³ and facing the entrance end of said channel. The several apertures are preferably formed by slitting the plate so that the deformation of the wall to form the deflecting elements will open these slits to provide the apertures and the several slits are preferably disposed vertically although they may be other than straight vertical slits. The air-deflecting plate 21 is provided with similarly formed apertures and deflecting elements, the transverse wall 21^b on one side of each inner crest 21^c being provided with apertures 21^d disposed at transversely spaced intervals and being deformed adjacent the rear edge of each of said apertures to provide deflecting elements 21^e projecting into the adjacent outer air channel B³ and facing the entrance end of said channel. The transverse wall 21^m on the other side of each crest 21^c is provided with the apertures 21ⁿ disposed at transversely spaced intervals staggered with relation to the apertures 21^d of the opposite wall and said wall 21^m is deformed adjacent the rear edge of each of said apertures to provide other deflecting elements 21^e projecting into the adjacent inner air passage B² and facing the entrance end of said air passage.

75. With these deflecting elements projecting into

75 With these deflecting elements projecting into

the several air channels and passages and facing the front of the radiator, it will be understood from an examination of Figs. 2 and 3 that the deflecting elements 20^r and 21^r split the air body in the inner air passages B² and deflect such split air currents through the associated apertures 20^d and 21^d into the adjacent air channels B³ and towards the respective fluid conduits A, as indicated by the arrows 30 in Fig. 2, and that the deflecting elements 20^r and 21^r split the body of air in the respective outer air channels B³ and deflect such split air currents away from the fluid conduits A and through the associated apertures 20^d and 21^d into the adjacent air passage B², as indicated by the arrows 31 in Fig. 3. With the relatively staggered disposition of these several deflecting elements, air currents are successively split from and recombined with the air bodies passing through the several air passages B² and B³, and since the adjacent walls of these air passages are disposed in different oblique directions the deflected air currents will be directed in laterally opposite oblique directions.

This arrangement extends the path of travel of a substantial part of the entrained air to appreciably increase its effectiveness in cooling the fluid conduits. 100

To further extend the path of travel of the deflected air currents, the deflecting elements are angled, the deflecting elements 20° and 20^r of 105 each plate 20 being angled upwardly and rearwardly to direct the air currents deflected thereby obliquely upwardly and rearwardly, as indicated by the arrows 32 in Fig. 4, and the deflecting elements 21° and 21^r of each plate 21 being 110 angled downwardly and rearwardly to direct the air currents deflected by these deflecting elements obliquely downwardly and rearwardly, as indicated by the arrows 33 in Fig. 4.

This cross flow of the deflected air currents 115 from front to rear of the radiator core in opposite oblique directions transversely and laterally and across adjacent air passages in substantially continuous paths promotes relatively long travel of the deflected air currents through the radiator 120 core to contribute greatly to a maximum cooling of the fluid conduits by the cooling air.

In the preferable embodiment of the invention it is desirable to provide a radiator core which may be used with either side facing the source of cooling air or that will function the same on air forced through the air passages in either transverse direction, and to this end the plates 20 and 21 are also deformed adjacent the forward edge of each of the several apertures to provide additional deflecting elements 20^u, 20^v, 21^w and 21^x, similar to the respective deflecting elements 20^s, 21^r, 21^t and 21^u, excepting that they face the opposite ends of the air passages. 125 130

In Fig. 5 only one of the air-deflecting plates 135 is associated with two adjacent zig-zag fluid conduits and in this modification the deflected air currents are directed only in one transverse oblique direction.

In Fig. 6 the air-deflecting unit comprising the 140 pair of air-deflecting plates as above described, is shown associated with two adjacent parallel straight fluid conduits, while in Fig. 7 a single air-deflecting plate is shown associated with two 145 of such straight fluid conduits.

Throughout this description such terms as vertical, front, rear, upwardly, downwardly and rearwardly, are used in a relative sense, it being obvious that the described radiator may be used not only in a vertical position but in any other 150

position and that the air may be forced there-through from either the front or the back.

While the form of construction herein illustrated and described is fully adapted to fulfill all 5 of the objects primarily stated, it is to be understood that we do not wish to limit the invention in this regard, for it is susceptible of embodiment in various other forms; all coming within the scope of the following claims.

10 We claim:

1. An air-deflecting unit adapted for disposal between adjacent fluid circulating members of a radiator, said unit comprising a pair of relatively thin plates transversely corrugated and disposed in crest coengaging relationship to provide a vertical series of inner air passages and two vertical series of outer air channels, one adjacent the outer wall of each plate, each of said plates having the transverse wall on one side of 15 each of said coengaging crests apertured at transversely spaced intervals and deformed adjacent the rear edge of each aperture to provide deflecting elements projecting into the adjacent inner air passage and facing the entrance end thereof 20 to split the body of air entrained through said inner air passage and deflect the split air currents into the adjacent outer air channel, said plates also having the transverse wall on the opposite side of each of said coengaging crests similarly apertured at transversely spaced intervals staggered with relation to said first named apertures and deformed adjacent the rear edge of each of 25 said apertures to provide other deflecting elements projecting into the adjacent outer air channel and facing the entrance ends thereof to split the air entrained through said outer air channel and deflect these split air currents into the adjacent inner air passage, the several deflecting elements of one of said pair of plates being angled upwardly and rearwardly to direct 30 their deflected air currents upwardly and rearwardly in an oblique direction, and the several deflecting elements of the other of said pair of plates being angled downwardly and rearwardly to direct 35 their deflected air currents downwardly and rearwardly in an oblique direction.

2. An air-deflecting unit adapted for disposal between adjacent fluid circulating members of a radiator, said unit comprising a pair of relatively thin plates transversely corrugated and disposed in crest coengaging relationship to provide a vertical series of inner air passages and two vertical series of outer air channels, one adjacent the outer wall of each plate, each of said plates having the transverse wall on one side of 40 each of said coengaging crests apertured at transversely spaced intervals and deformed adjacent the rear edge of each aperture to provide deflecting elements projecting into the adjacent inner air passage and facing the entrance end thereof to split the body of air entrained through said inner air passage and deflect the split air currents into the adjacent outer air channel, said plates also having the transverse wall on the opposite side of each of 45 said coengaging crests similarly apertured at transversely spaced intervals and deformed adjacent the rear edge of each aperture to provide other deflecting elements projecting into the adjacent outer air channel and facing the entrance ends thereof to split the air entrained through said outer air channel and deflect these split air currents into the adjacent inner air passage, the several deflecting elements of one of said pair of plates being angled upwardly and rearwardly to direct 50 their deflected air currents upwardly and rearwardly in an oblique direction, and the several deflecting elements of the other of said pair of plates being angled downwardly and rearwardly to direct 55 their deflected air currents downwardly and rearwardly in an oblique direction.

apertures and deformed adjacent the rear edge of each of said apertures to provide other deflecting elements projecting into the adjacent outer air channel and facing the entrance ends thereof to split the air entrained through said outer air channel and deflect these split air currents into the adjacent inner air passage, the several deflecting elements of one of said pair of plates being angled upwardly and rearwardly to direct 60 their deflected air currents upwardly and rearwardly in an oblique direction, and the several deflecting elements of the other of said pair of plates being angled downwardly and rearwardly to direct 65 their deflected air currents downwardly and rearwardly in an oblique direction, said plates being similarly deformed adjacent the forward edge of each aperture to provide additional deflecting elements facing rearwardly to permit 70 said plates to function similarly on air entrained through said unit in reverse direction.

3. In a radiator, the combination of: relatively spaced fluid circulating members each comprising a pair of relatively thin transversely corrugated plates disposed in intermeshing relationship and joined along their longitudinal edges 75 with their intermediate portions spread apart to provide a zig-zag fluid conduit; and an air-deflecting unit disposed between said fluid circulating members, said air-deflecting unit comprising a pair of relatively thin plates transversely corrugated and disposed with their inner crests coengaged to form a vertical series of inner air passages and with their outer crests engaging the crests of the respective adjacent fluid circulating members to form therewith vertical series 80 of outer air passages, each plate of said air-deflecting unit having the transverse wall on one side of each of said inner crests apertured at transversely spaced intervals and deformed adjacent the rear edge of each aperture to provide 85 deflecting elements projecting into the adjacent inner air passage and facing the entrance end thereof to split the air in said inner air passage and deflect the split air currents into the adjacent outer air passage and towards the adjacent fluid 90 circulating member, said plates also having the transverse wall on the opposite side of each of said inner crests similarly apertured at transversely spaced intervals and deformed adjacent the rear edge of each of said apertures to provide 95 other deflecting elements projecting into the adjacent outer air passage and facing the entrance end thereof to split the air in said outer air passage and deflect these split air currents away from the adjacent fluid circulating member and into the adjacent inner air passage, the several 100 deflecting elements of one of said pair of plates being angled upwardly and rearwardly to direct their deflected air currents upwardly and rearwardly in an oblique direction, and the several 105 deflecting elements of the other of said pair of plates being angled downwardly and rearwardly to direct 110 their deflected air currents downwardly and rearwardly in an oblique direction.
